REED TRIMMER

Lucien Cordier, Arnouville les Gonesse, France

Application April 9, 1951, Serial No. 219,952

Claims priority, application France
November 7, 1950

2 Claims. (Cl. 30—229)

1

This invention relates to reed trimmers and more particularly to an improved actuating device therefor.

It is known that musician performers such as clarinetists, saxophonists, oboists and other players of reed instruments must trim their reeds whenever these have become deteriorated or worn by continuously blowing or pinching them with the lips or for any other cause.

To do so they use a cutting tool fitted with a punching tool having the desired rounded shape. This cutting tool or reed trimmer consists as a rule of a die member on which the reed to be trimmed is placed and then cut by exerting a relatively strong pressure upon the punching member. Thin reeds are thus easily cut but when thick reeds are to be trimmed or when the trimming device has been used many times the pressure to be exerted on it is such that many musicians, who are generally more nimble than strongfingered, find it rather difficult to perform this operation.

It is the scope of this invention to avoid this drawback of existing reed trimmers by providing an improved reed trimmer characterized essentially by the fact that the punching member thereof is actuated through the medium of a self-returning lever whereby the hardest and thickest reeds may be cut quickly and regularly with a small effort and without the slightest difficulty.

These and other characteristic features of the invention will appear clearly from the following description if reference is made to the affixed drawing illustrating diagrammatically by way of example one possible embodiment of the invention. In the drawing:

Fig. 1 is an improved reed trimmer the punching member of which is actuated through the medium of a lever;

Fig. 2 is a sectional view, at a greater scale, of the reed trimmer in its inoperative position;

Fig. 3 is an elevational broken fragmentary view of the reed trimmer in its operative position;

Fig. 4 is an end view of the reed trimmer.

The improved reed trimmer according to the invention (Fig. 1) consists of a stamped plate acting both as a die member 2 and a punching member 3, the free end 3a of the latter facing the cutting edge of the die member 2 and is normally slightly offset from the plane of the latter. The stamped plate forming the die and punch members 2, 3 is mounted on a frame member 7 formed with an aperture 8. On the bottom end of the frame member is slidably mounted an adjusting

slide 9 held thereon by a leaf spring 10 fast with the slide 9 and bearing on either sides of an aperture 11. A spring clip 12 is hingedly mounted at 13 on the rear face of the slide 9 and formed with a head 12a. A screw 14 formed with a knurled head engages a cooperating threaded bore in the slide and is held against axial motion by the bottom end of the frame member 7 so that by turning the screw in one or in the other direction the slide may be moved up or down at will.

The reed trimmer also comprises an actuating lever 15 consisting of two shaft portions 15a journaled in suitable recesses provided in the side portions of the frame member 7, a cam portion 15b kept in constant engagement with the punching member 3 by the offset position and resiliency of the latter, and a control portion 15c which is preferably so bent as to fit around the trimmer frame 7 in order to reduce its overall dimensions. Also preferably, this control portion 15c is formed with gripping means and urged in its inoperative position by the resiliency of the punching member against a check member 16 fast or formed integrally with the frame member 7.

The improved reed trimmer described above is used as follows:

After the reed to be trimmed is placed on the face 3b of punch 3 by engaging the end to be cut in the gap formed between the die member 2 and said punch 3, the opposite portion of the reed is placed on the slide 9 and held thereon by means of the spring clip 12 which is readily closed by the engagement of its head 12a with the cooperating edge of the slide. Then the screw 14 is turned in the direction and to the extent corresponding to the amount of reed material to be cut off. Finally, by merely exerting a moderate pressure on the lever 15 (Fig. 3) the reed is trimmed without any appreciable effort. As a matter of fact, by rotating the shaft portions 15a of the lever in the anticlockwise direction the cranked portion 15b thereof will exert a relatively high pressure against the punching member 3 whereby the reed end will be firstly clamped and then cut off by the cooperating cutting edges of die member 2 and free end 3a of punching member 3. Thus, a spotless punching of the reed is obtained without effort and the reed is ready for use.

It will be obvious that many alterations may be brought to the embodiment shown and described herein without departing from the spirit and scope of the invention. Thus, the cranked portion 15b of the actuating lever 15 may be bent to any desired shape provided it exerts the afore-

described pressure against the free end 3a of the punching member 3.

What I claim is:

1. A reed trimmer comprising in combination an oblong frame member formed with an oblong aperture, a plate member fast with said frame member and formed with a die portion having a cutting edge extending towards one end of said frame member and with a punching resilient portion having a cutting edge extending towards the other end of said frame member, said punching portion being at its juncture with said plate member bent on one side relative to the plane of said plate member and having an inherent resiliency such as to constantly urge same toward said side thereby forming between said punching portion and said die portion a gap, in which the reed portion to be trimmed may be introduced to the desired extent, an extension of said one end of said frame member, a slide slidably mounted on said extension, means for fixing the reed to be trimmed on said slide, and means for adjustably controlling the displacement of said slide along said extension, a pin disposed transversely of said punching portion on the side where said punching portion is bent and comprising a pair of shaft portions journaled in the side portions of said frame member, one of said shaft portions being formed with a bent lateral extension forming an actuating lever fitting the external contour of said other end of said frame member, a cranked portion of the pin itself against which said punching portion is urged by its resiliency, said cranked portion of the pin being adapted to hold said punching portion in a plane slightly offset from that of said die portion when said actuating lever is substantially in the plane of said frame member, and adapted to engage said punching portion for urging it towards said cutting edge of said die portion when said actuating lever is moved angularly from its position substantially in the plane of said frame member, i. e. its inoperative position, a check member fast with the external contour of said other end of said frame member, said actuating member being urged against said check member in inoperative position by the resiliency of said punching portion.

2. A reed trimmer comprising in combination an oblong frame member formed with an oblong aperture, a plate member fast with said frame member and formed with a die portion having a cutting edge extending towards one end of said frame member and with a punching resilient portion having a cutting edge extending towards the other end of said frame member, said punching

portion being at its juncture with said plate member bent on one side relative to the plane of said plate member and having an inherent resiliency such as to constantly urge same toward said side thereby forming between said punching portion and said die portion a gap, in which the reed portion to be trimmed may be introduced to the desired extent, an extension of said one end of said frame member, a slide slidably mounted on said extension, means for fixing the reed to be trimmed on said slide, and means for adjustably controlling the displacement of said slide along said extension, a pin disposed transversely of said punching portion on the side where said punching portion is bent and comprising a pair of shaft portions journaled in the side portions of said frame member, one of said shaft portions being formed with a bent lateral extension forming an actuating lever fitting the external contour of said other end of said frame member, a cranked portion of the pin itself against which said punching portion is urged by its resiliency, said cranked portion of the pin being adapted to hold said punching portion in a plane slightly offset from that of said die portion when said actuating lever is substantially in the plane of said frame member, and adapted to engage said punching portion for urging it towards said cutting edge of said die portion when said actuating lever is moved angularly from its position substantially in the plane of said frame member, i. e. its inoperative position, a check member fast with the external contour of said other end of said frame member, said actuating member being urged against said check member in inoperative position by the resiliency of said punching portion.

LUCIEN CORDIER.
